(57) **CLAIM**

The ornamental design for an ice-fishing tip-up as shown.

DESCRIPTION

FIG. 1 is a top, right perspective view of one embodiment of an ice fishing tip-up with the flag up.

FIG. 2 is a front elevational view of the ice fishing tip-up of FIG. 1.

FIG. 3 is a rear elevational view of the ice fishing tip-up of FIG. 1.

FIG. 4 is a first side elevational view of the ice fishing tip-up of FIG. 1.

FIG. 5 is a second side elevational view of the ice fishing tip-up of FIG. 1.

FIG. 6 is a top plan view of the ice fishing tip-up of FIG. 1.

FIG. 7 is a bottom plan view of the ice fishing tip-up of FIG. 1.

FIG. 8 is a top, right perspective view of the ice fishing tip-up of FIG. 1 with the flag down.

FIG. 9 is a front elevational view of the ice fishing tip-up of FIG. 8.

FIG. 10 is a rear elevational view of the ice fishing tip-up of FIG. 8.

FIG. 11 is a first side elevational view of the ice fishing tip-up of FIG. 8.

FIG. 12 is a second side elevational view of the ice fishing tip-up of FIG. 8.

FIG. 13 is a top plan view of the ice fishing tip-up of FIG. 8; and,

FIG. 14 is a bottom plan view of the ice fishing tip-up of FIG. 8.

1 Claim, 14 Drawing Sheets
